HENRY M. GLEASON, OF SAN FRANCISCO, CALIFORNIA, ASSIGNOR TO CHASE COMPANIES INC., OF WATERBURY, CONNECTICUT, A CORPORATION.

MACHINE FOR CARDING SAFETY PINS, ETC.

Application filed October 8, 1924. Serial No. 742,363.

This invention relates to machines and processes for carding safety pins or generally similar articles by which the safety pins in the closed position in which they are finished by the forming machines and processes may have their point sections or reaches inserted into the relatively short slots of a slotted pin card and then secured to the card by a thin pasteboard or other paper locking strip which is inserted or threaded through the opening between the inserted sections of the safety pins and the rear face of the pin card, which is preferably in arched or bowed up position. The carding machine may comprise a number of inclined pin chutes down which streams of safety pins may be fed by gravity from sorting machines such as are shown in the Gleason Patent 1,456,546, of May 29, 1923, by which the safety pins may be arranged with their head ends foremost, if desired. An oscillating cut-off gate or other feeding mechanism may be arranged to periodically deliver a dozen or other desired series of safety pins from these chutes or any other suitable feeding devices into a pin carrier which may be of skeleton construction and slotted or formed to support the safety pins in one or more parallel rows and preferably substantially perpendicular to the general plane of the pin card, which may be fed in below the carrier. The pin card may be arched or bowed up in any suitable way as by forcing a suitable card support such as a slotted carding block up against the pin card which may force its central portion up into arched position between two lateral members or bars that may be formed on the pin carrier, so that the slots in the card come into alignment with the pins which enter the slots in the card and corresponding transverse slots or clearance grooves which may be provided in the carding block below, the pins being held or forced down in this position by a descending pressure member or follower, if desired. At this point the thin cardboard or other locking strip may be inserted between the rear surface of the arched up pin card and the portions of the safety pins projecting through the card slots to definitely hold the safety pins in position as soon as the pin card is released from its bowed up position and allowed to straighten out sufficiently so that the pins force the locking strip against the card back. This is a desirable and efficient method of carding closed safety pins without opening them and sticking the pointed ends through a card and subsequently closing them; and cooperating elements of the types above referred to may be combined into carding machines and operated at the proper times by any suitable means such as positive cams or spring opposed cam devices or treadle connections, so as to be largely or wholly automatic in their operation and have large capacity.

An illustrative machine embodying this invention is shown in a somewhat diagrammatic way in the accompanying drawings in which

Fig. 1 is a side elevation.

Fig. 2 is an enlarged front elevation looking in the direction of the arrow A in Fig. 1.

Fig. 2^a is a transverse sectional detail taken along the line 2^a of Fig. 2.

Fig. 3 is an enlarged plan view looking in the direction of the arrow B in Fig. 1.

Fig. 4 is a transverse section taken along the line 4—4 of Fig. 2, the parts being in their positions at the beginning of a carding cycle.

Fig. 5 is a similar view but with the parts shown at the completion of the carding cycle before the release of the card.

Fig. 6 is a perspective view of the carding block.

Fig. 7 is a plan view of a card of safety pins such as may be formed on this machine.

Fig. 8 is a plan view of the slotted pin card that may be used, and

Fig. 9 is a similar view of the locking strip therefor.

In carrying out this invention, twelve streams of closed safety-pins 15, of any approved construction and provided with heads, may be fed by gravity through a gang of inclined chutes 16, the upper ends of which are connected with some source of supply, such, for instance, as sorting machines of said patent by which the pins are fed into the upper ends of the chutes with their corresponding ends foremost, preferably their head-ends, as shown. The lower ends of the said inclined chutes 16 register with the upper ends of twelve correspondingly spaced inclined channels 17 traversing the upper face of an inclined delivery-plate 18 mounted on the inclined upper face of

the head 19 of a bracket 20 secured to a machine frame or bench 21.

The closed pins 15 may be discharged by gravity from the lower ends of the said channels 17 into an inclined skeletonized pin carrier unit reciprocating at right angles to the plane of the said channels. As shown in Fig. 4, the said carrier may comprise a transversely-arranged, notched inner bar 22 and a parallel notched outer bar 23, the space separating these two parallel bars being something less than the length of the pins, so that their middle portions are unsupported and exposed. The said bar 22 is secured to the upper ends of two plates 24, the lower ends of which are secured to the inner edges of the respective ends of a yoke piece 25 shown in Fig. 2 as mounted upon the upper end of a tubular extension 26 reciprocating upon a guide-post 27 rigidly mounted at its upper end in the stationary carding block 28 of the carding unit. The ends of the outer bar 23 are similarly secured to the upper ends of two plates 29, the lower ends of which are secured to the ends of the outer edge of the coupling or yoke piece 25 aforesaid. The said plates 29 may be formed with guide slots 30 receiving bolts 31 entering the carding block 28, so as to provide for guiding and steadyng the skeleton pin carrier in its reciprocating movement at right angles to the delivery-plate 18 aforesaid.

As shown in Fig. 3, the bar 22 supports a plate 32 which is parallel with it and which may be formed with twelve equally spaced notches 33 respectively located in line with the channels 17 and registering with narrower notches 34 formed in the bar 22, these notches 33 and 34 receiving and locating the coiled rear ends of the pins 15. The bar 23 is formed with a series of similarly spaced notches 35 arranged in line with the notches 34, from which they are separated by a distance slightly wider than the width of the carding block 28, but not so wide as the length of the pins, which may thus be supported by their ends, with free middle portions. The bar 23 also supports a stop plate 36 provided with twelve pockets 37 located in line with the notches 35 but larger than the same and adapted to receive the head-ends of the pins, as shown in Fig. 5, the opposite walls of these notches 37 being preferably beveled, as at 38, to assist in guiding the pins into their ultimate positions in the pockets 37. The pin carrier thus supports the safety pins in such positions that they can be inserted or forced into the similarly spaced slots of a pin card which may be held in any suitable card holder so as to be substantially flat in some cases; although the insertion and securing of the pins is usually facilitated where the pin slots are transversely arranged by the

preliminary transverse arching up of the pin card by any suitable bending members cooperating with the card holder or movable with respect thereto such as lateral bending members engaging the upper face 70 of the card on each side of the center line. The card holder or support may be the carding block 28 rigidly secured by screws 43 to a flange 44 on the main frame 20 and may be arranged parallel with the pin carrier; 75 and the upper surface of the carding block is preferably formed as is shown in Fig. 6 with twelve transverse clearance grooves 39 arranged in line with the notches 34 and 35 and the pockets 37 of the reciprocating pin 80 carrier unit already described. At their ends, the clearance grooves 39 may intersect upstanding ribs 40 between which the inserted locking strips 42 may be guided, and these bending or crimping ribs may have 85 rounded outer bending surfaces preferably extending throughout the card at the lateral portions of the carding block, so as to assist the arching up of the card by the relatively movable lateral bars 22, 23 which may be 90 mounted on the pin carrier in some cases.

The pin cards 41 may be fed to the carding block by any suitable feeding devices which may comprise a card tray or support 45 secured to the left hand portion of the carding block 28 and mounted so that its lower surface is at the right level to form a guide for the pin card as it is longitudinally fed over the carding block. In this connection a guide or feeding channel may advantageously be formed so as to extend from the card tray more or less through the length of the feeding block over which the pin card is fed. This feeding channel may comprise the offset or clearance portions 46, 47 of the plates 24 and 27 shown in Figs. 1 and 3 and the inner guiding edge 52 against which the pin card may rest and one or more outer spring guides or strips such as 53 projecting from the inner edge of a rectangular housing 54 secured, for instance, to a bracket 55 attached to the outer face of the carding block, which together may thus form a support or holder for the pin card. Suitable longitudinal stops may advantageously be provided to position the cards longitudinally with respect to the carding block, such as one or more adjustable or spring pressed plunger stops 50 shown in Fig. 2 as movably mounted as in the upper end of the right hand plate 29 and normally forced into the position indicated with respect to the carding block by the connected springs 51. An adjustable stop 49 having an upwardly inclined end may be mounted in a recess 48 in the carding block and yieldably held in adjusted position by the screw shown in Fig. 3 at the left of the resilient part of this stop. By giving the right hand ends of this stop an upwardly sloping con-

tour; the pin card can ride up over this downwardly yielding end of the stop and then fall down behind it so as to be accurately positioned by this stop and the operating spring pressed plunger stops 50 engaging the forward end of the card. It is not, however, necessary to use this stop 49 where the pin cards are mechanically fed to the carding block, which can be effected by any suitable cooperating card feeding devices such as the feeding slide 148 mounted in grooves 150 in the carding block which may be extended outward for this purpose. This slide may at one or more points along the width of the pin card project upward above the surface of the card tray to nearly the thickness of one of these pin cards 41 so as to feed forward the lower card from a stack 141, the other cards being held in place as by one or more adjustable separators or gates 146 which may be vertically adjusted and held as by one or more bolts 147. With such slotted cards sticking is minimized by rearwardly inclining the card stack at its forward end as indicated in Fig. 2 so that the front edges of each of these card slots normally rest on the flat surface of the card below. This feeding slide 148 may be reciprocated at the proper time by any suitable mechanism such as a lever 149 pivoted or otherwise connected to the slide and actuated as by the auxiliary treadle 151 normally raised by the light spring 152 some distance above the treadle 75 as determined by the loose connecting bolts 153. A cable or chain 154 connected with this treadle 151 may pass over one or more pulleys 155 and be connected to the lever 149 near enough to its fulcrum, which is preferably mounted in a vertically movable fulcrum block 156, so as to give this card feeding slide the desired forward throw, the extent of which is determined by the adjustable stop 148' in the slide engaging the frame, after which idle expansion of the connection spring 154' occurs, the rearward movement of the slide and lever being effected by the lighter spring 157. In this way a pin card may be fed into position on the carding block before the treadle 151 engages the main treadle 75 and actuates it to operate the other parts of the machine.

Similar feeding devices may be used to feed the locking strips 42 across the carding block after the pin card has been arched up and the pins inserted into the card slots; and these feeding means may comprise a tray 56 and suitable cooperating feeding guides so as to guide these locking strips into the central space between the ribs 40 on the carding block. If desired, these locking strips may be mechanically fed by any suitable cooperating feeding means such as a feeding slide 158 mounted to recipro-

cate in guides in the right hand end of the carding block 28 or its extension and a suitable card box may be formed on the tray comprising the members 159 and a feeding separator or gate 160 which is preferably vertically adjustable through suitable bolts 161 so as to hold in place all of the stack 142 of locking strips except the lowest one which may be engaged by the front edge of the slide 158, preferably considerably narrower than these locking strips and projecting up slightly beyond the surface of the tray or feeding guide, as shown in Fig. 2. This locking strip slide may be automatically actuated by any suitable mechanism such as cams or treadles and, if desired, a supplemental feeding treadle 163 normally held up against the stop or pin 164 by the spring 165, may be engaged by the main treadle 75 after it has actuated the other parts of the mechanism so that its further downward movement, after the adjustable limiting collar 166 shown in Fig. 5 stops the downward movement of the rod 72, extends the spring 173 in the chain connection 73 and moves this treadle 163 and the connected chain or cable 164', which through any suitable connections may operate the spring pressed lever 165' connected to the slide 158 as in the case of the feeding slide 148.

The lowermost safety pins of the columns or streams of pins in the respective chutes 16, are separated from the pins above them so as to feed a series of twelve safety pins, for instance, from the twelve chutes by means of any suitable rocking gate as 59 shown in Fig. 3 and preferably formed upon its upper edge with twelve fingers 60 spaced apart to enter the upper ends of the channels 17 in the delivery-plate 18, while the lower edge of the said gate is formed with twelve corresponding fingers 61, similarly entering the channels 17, these two sets of fingers 59 and 61 being sufficiently separated from each other to accommodate, without binding, the full length of a safety pin of the particular size being carded. The said gate is furnished at its ends with downwardly-extending parallel arms 62 receiving screw studs 63 entering the ends of the plate 18 upon which the gate is thus pivoted for rocking movement. The said arms 62 are provided at their lower ends with pawls 64 coacting with teeth 65 upon the upper edges of forwardly inclined rock arms 66 overhanging the plate 18 and respectively secured to the opposite ends of a rock shaft 67 in the head 19. Springs 68, connecting the arms 66 with the studs on which the pawls 64 are hung, exert a constant effort to swing the gate 59 into its pin delivering position, as shown in Fig. 5. The outer ends of the arms 66 are connected by a bar-like follower 69, the function of which is

to engage with all of the pins of a group of pins after they have been installed in the skeletonized pin carrier, so as to steady them and prevent their displacement and 5 also to follow them in their downward movement with the carrier and by its pressure assist in their insertion into the slots 41^a of the cards 41. The said follower 69 may be moved for the purpose described, by 10 means of a yoke 70 the ends of which, shown in Figs. 1 and 3 are connected with the respective arms 66 and which is itself connected by a knuckle joint 71 with the upper end of a treadle rod 72, the lower 15 end of which is attached to a chain 73 running over a pulley 74 and connected at its lower end with a foot treadle 75 having the usual light lifting-spring 76.

As shown in Fig. 5 a sleeve 77, which 20 for convenience I may call the carrier actuating sleeve, may be loosely mounted upon the lower end of the rod 72 and has sliding bearing at 77^a in the frame 20, its upper end coaxing with the lower end of the 25 said knuckle 71, and its lower end resting upon the upper face of an operating lever 78 having a slot through which the rod 72 passes and pivoted in a bracket 79 attached to the frame 20. The outer end of the lever 30 78 is connected to the pin carrier as by being forked and embracing the tubular extension 26 between two collars 80 shrunk thereupon. For lifting the follower 69 into its elevated position and, at the same 35 time, restoring the pin carrier to its elevated position and rocking the gate 59 into its charging position, two springs 81 may be used having their upper ends connected to the frame and having their lower ends 40 connected to the ends of a cross bar 82 located upon the lower end of a tube 83 secured by a rivet 84 to the treadle rod 72.

The operation of this illustrative machine in carrying out the process in one way is 45 as follows. In the first place, the operator may with her left hand, slide one of the cards 41 from a pile on the tray 45 from left to right through the card feeding guides and over the grooved portion of the carding 50 block, so as to position it between the four stops 49, 50, 52, and 53 (Figs. 3 and 4) thereon and bring its slots 41^a into register with the transverse clearance grooves 39 in the block. The treadle 75 may now be depressed, so that the rock-arms 66 are swung 55 down to disengage their teeth 65 from the pawls 64 carried by the gate 59. The springs 68 now act to rock the gate upon its studs 63 into its discharging position in which its 60 fingers 60 enter the upper ends of the channels 17 in the plate 18 to intercept or hold back the pins above, while its lower fingers or teeth 61 are lifted from the said channels, whereby the series of safety pins already 65 within the gate between the gate fingers are

released and permitted to slide down into the open top pin carrier, so as to assume the position indicated in broken lines in Fig. 4. The operator can thus readily detect and rectify any irregularities in this 70 separated series of safety pins such as the reversed position or absence of one of the pins of the series as occasionally occurs; and this rectification is greatly facilitated by the accessible open top arrangement of 75 the pin carrier at this period in the operation of the machine. The operator may then 80 continue the downward movement of the treadle 75, and consequently the continued downward movement of the arms 66 brings 85 the follower 69 into contact with the upper portions or reaches of all of the pins, which are now arranged in vertical planes in the several notches of the carrier, so that the 90 pins are firmly held against upward displacement therein. The parts are so proportioned and their movements are so timed that when the bar 69 comes down on the pins in the carrier, the lower end of the knuckle-joint 71 engages with the upper end of the 95 slidable actuating sleeve 77, the lower end of which now pushes downward upon the lever 78, which in turn acts through the tubular extension 26 to draw the loaded carrier downward over the pin card 41 positioned as described upon the carding block. 100 The initial downward movement of the carrier causes its side bars 22 and 23 to engage with the overhanging side edges of the card, whereby the card is arched up or "crimped" as the expression is, over the crimping ribs 40 of the block, its slotted central portion being upwardly bowed, as shown in Fig. 5, and its edges being pressed toward or upon the rear and front faces of 105 the block. The continued downward movement of the carrier may effect the insertion of the exposed lower reaches of the rectified series of spaced pins through the correspondingly spaced pin slots 41^a of the card 110 and into the clearance grooves 29 of the block and therefore in position, as shown in Fig. 5, where they will not interfere with the insertion of a locking-strip 42, which the operator may now slide from right to 115 left from the strip-pile on the tray 56 and may thus thread the strip successively through the pins, the movement of the strip from right to left being continued until its 120 ends are coincident with the ends of the cards. The strip is now interposed between the concave back or under face of the card and the middle portions or reaches of the pointed ends of the pins, which inserted 125 portions are at this time lying in the bottoms of the transverse clearance grooves in the carding block. Pressure upon the treadle 75 now being removed or relieved, the springs 81 promptly restore the parts of 130 the machine to the positions in which they

appear in Figs. 1 to 4 inclusive, in which they are shown in their positions just prior to the beginning of a carding cycle. As the pin-carrier unit is thus lifted away from the carding-block, the edges of the pin card are more or less released; and the parts of the machine then assuming the position shown in Fig. 4, the card and pins may be removed from the carrier manually or 10 through any suitable lifting or discharging members not shown for the sake of clearness.

This invention has been described in connection with a number of embodiments, 15 forms, proportions, parts, arrangements, materials, conditions, number and order of steps, methods of construction, operation and use, to the details of which disclosure of the invention is not of course to be limited; since 20 what is claimed as new and what is desired to be secured by Letters Patent is set forth in the appended claims.

I do not, in this case, claim any of the 25 specific mechanisms illustrated, described and claimed in the co-pending application of Ernest H. Webb, filed April 12, 1922, Serial No. 551,972.

What I claim is—

1. In a machine for carding safety pins, 30 pin feeding mechanism, a pin carrier unit to which pins are supplied in predetermined systematic arrangement by the said machine, a carding unit upon which slotted cards are placed, and means for bodily moving one of 35 the said units with respect to the other for the insertion of portions of the pins into slots in the card.

2. In a machine for carding safety pins, 40 pin feeding mechanism, a pin carrier unit to which pins are supplied in predetermined systematic arrangement by the said machine, a carding unit receiving and positioning a slotted card, and means for moving one of 45 the said units bodily toward the other for the insertion of portions of the pins into slots in the card and for holding them in such inserted positions preparatory to securing them to the card.

3. In a machine for carding safety pins, 50 pin feeding mechanism, a pin carrier unit to which pins are fed in predetermined systematic arrangement by the said machine, a carding unit receiving and positioning a slotted card, and means for moving one 55 unit toward the other and for crimping the card, whereby portions of the pins are entered into the slots in the crimped card, preparatory to being secured thereto.

4. In a machine for carding safety pins, 60 pin feeding mechanism, a pin carrier unit to which pins are supplied in predetermined systematic arrangement by the said machine, a carding unit for receiving, positioning and crimping a slotted card, and means 65 for moving the said carrier unit into co-

operative relation with the said carding unit, whereby portions of the pins are entered into the slots in the card, preparatory to being secured thereto.

5. In a machine for carding safety pins, 70 pin feeding mechanism, a skeleton pin carrier to which pins are fed in predetermined systematic arrangement by the said machine so as to expose the intermediate portions thereof, a carding unit for the reception and crimping of a slotted card, and means for moving one unit toward the outer unit for the entrance of the exposed intermediate portions of the pins into the slots of the card, preparatory to securing the pins 80 thereto.

6. In a machine for carding safety pins, 85 pin feeding mechanism, a skeleton pin carrier to which pins are supplied in predetermined systematic arrangement by the said machine, a carding unit for the reception and crimping of a slotted card, means for moving one unit toward the other, whereby intermediate reaches of the pins are inserted into the slots in the card, preparatory 90 to being secured thereto, and means for steadyng the pins in the pin carrier during the said movement of one unit toward the other for the insertion of the pins into the slots of the card.

7. In a machine for carding safety pins, 95 pin feeding mechanism, a pin carrier to which the pins are fed by the said machine and in which the middle portions or reaches of the pins are exposed, a carding block 100 formed with transverse clearance grooves for the reception of the exposed reaches of the pins and providing for the crimping of the card, and means for moving the said carrier toward the said block for the insertion of reaches of the pins through slots in the card into the said grooves preparatory to securing the pins to the card.

8. The apparatus for carding safety pins, 110 comprising a card holder, means to arch up a slotted pin card supported by said card holder, a cooperating pin transfer device having a series of spaced pin slots corresponding to the slots in said card, and releasable pin supports cooperating with said transfer device to support a series of safety pins in alignment with the slots in said card.

9. In a machine for carding safety pins etc. a carding block formed with a spaced series of clearance grooves and with lateral card bending ribs, a relatively movable pin carrier having side bars adapted to pass on each side of said carding block to transversely arch up an interposed transversely slotted pin card arranged with its slots in substantial alignment with said clearance grooves, means to support a series of safety pins in said carrier in substantial alignment with said clearance grooves, card feeding devices to automatically feed slotted 120 125 130

pin cards between said block and carrier, and locking strip feeding devices to automatically feed paper locking strips between the concave face of the pin card and the reaches of the safety pins inserted through the card slots.

10. In a machine for carding safety pins, etc. a carding block formed with lateral card bending ribs, a relatively movable pin carrier means adapted to transversely arch up a transversely slotted pin card, means to support a series of safety pins in said carrier in substantial alignment with said clearance grooves, and card feeding devices to automatically feed slotted pin cards between said block and carrier.

11. In a machine for carding safety pins etc. a carding block formed with card bending lateral portions, a relatively movable pin carrier having side members adapted to pass on each side of said carding block to transversely arch up an interposed transversely slotted pin card and insert the point reaches of the safety pins held in said carrier through the slots in the pin card between said carding block and carrier, and feeding devices to feed automatically paper locking strips between the concave face of the pin card and the inserted reaches of the safety pin.

12. In a machine for carding safety pins etc. a carding block, a relatively movable pin carrier having side members adapted to pass on each side of said carding block to transversely arch up an interpose transversely slotted pin card and insert reaches of the safety pins held in said carrier through the slots in the pin card between said carding block and carrier, and feeding devices to feed paper locking strips between the concave face of the pin card and the inserted reaches of the safety pins.

13. In a machine for carding safety pins etc. a carding block, a relatively movable pin carrier to insert reaches of the safety pins held in said carrier through the slots in the pin card between said carding block and carrier, and feeding devices for feeding locking strips between the concave face of the pin card and the inserted reaches of the safety pins.

14. In a machine for carding safety pins etc. a carding block formed with a spaced series of clearance grooves, a relatively movable pin carrier having side members adapted to pass on each side of said carding block to transversely arch up a transversely slotted pin card arranged between them with its slots in substantial alignment with said clearance grooves, and means to feed a series of safety pins to said carrier and support them in substantial alignment with said clearance grooves.

15. In a machine for carding safety pins, etc., a carding block, relatively movable pin carrier, bending members adapted to pass on

each side of said carding block to transversely arch up a transversely slotted pin card arranged between them, and means to feed a series of safety pins to said carrier and insert them in the card slots.

16. In a machine for carding safety pins, etc., a carding block, a relatively movable pin carrier having side bars adapted to pass on each side of said carding block to support and transversely arch up a transversely slotted pin card arranged between the carding block and carrier, means to insert portions of the safety pins in said carrier in the slots in said pin card, card feeding devices arranged at one end of said carding block to feed slotted pin cards between said block and carrier, and locking strip feeding devices at the other end of said carding block to feed paper locking strips between the opposing concave face of the pin card and the portions of the safety pins inserted through the card slots.

17. In a machine for carding safety pins, etc., a carding block, a relatively movable pin carrier to support and transversely arch up a transversely slotted pin card arranged between the carding block and carrier, means to insert portions of the series of safety pins in said carrier in the slots in said pin card, card feeding devices to feed slotted pin cards between said block and carrier, and locking strip feeding devices to feed paper locking strips between the opposing concave face of the pin card and the portions of the safety pins inserted through the card slots.

18. In a machine for carding safety pins, etc., a carding block, a relatively movable pin carrier to support a slotted pin card arranged between the carding block and carrier, means to insert portions of the series of safety pins in said carrier in the slots in said pin card, and locking strip feeding devices for feeding locking strips between the opposing face of the pin card and the portions of the safety pins inserted through the card slots.

19. In a machine for carding safety pins, etc., a card support, a relatively movable pin carrier having means to support and align a series of safety pins by their ends and insert them into the pin slots of a pin card on said card support, card feeding devices arranged at one side of said card support for feeding slotted pin cards to said card support, and locking strip feeding devices on the other side of said card support for feeding locking strips between the inserted portions of the safety pins and the opposing face of the pin card.

20. In a machine for carding safety pins, etc., a card support, a relatively movable pin carrier having means to support a series of safety pins and insert them into the pin slots of a pin card on said card support, card feeding device arranged at one side of

- said card support for feeding slotted pin cards to said card support, and locking strip feeding devices on the other side of said card support for feeding locking strips thereto.
21. In a machine for carding safety pins, etc., a carding block formed with a spaced series of transverse pin grooves and with card bending portions, a relatively movable pin carrier having side members adapted to pass on each side of said carding block to transversely arch up a slotted pin card arranged between them with its slots in substantial alignment with said grooves, mechanism to feed a series of safety pins to said carrier and support them in substantial alignment with said grooves, and locking strip feeding devices cooperating with said carding block to automatically feed paper locking strips between the opposing concave face of the pin card and the portions of the safety pins inserted through the card slots.
22. In a machine for carding safety pins, etc., a carding block formed with a spaced series of transverse pin grooves, a relatively movable pin carrier cooperating with a slotted pin card which is arranged between the said blocks and pin-carrier with its slots in substantial alignment with said grooves, mechanism to feed a series of safety pins to said carrier and support them in substantial alignment with said grooves, and locking strip feeding devices cooperating with said carding block for feeding locking strips between the opposing face of the pin card and the portions of the safety pins inserted through the card slots.
23. In a machine for carding safety pins, etc., a carding block, a relatively movable pin carrier cooperating with a slotted pin card which is arranged between the said block and pin-carrier, and devices cooperating with said carding block for feeding locking strips between the opposing face of the pin card and the portions of the safety pins inserted through the card slots.
24. In a machine for carding safety pins, pin feeding mechanism, a cooperating open top pin carrier having slots to support a spaced series of safety pins and to allow rectification of irregularities therein, a relatively movable carding block formed with correspondingly spaced clearance grooves and having means to arch up a slotted pin card in connection with said carrier and to force portions of said safety pins through the card slots, and means for inserting a paper locking strip between the concave face of the pin card and the inserted portions of the pins.
25. In a machine for carding safety pins, pin feeding mechanism, a cooperating pin carrier to accessibly support a spaced series of safety pins and to allow rectification of irregularities therein, a relatively movable
- card support for a slotted pin card and means to insert portions of said safety pins through the card slots.
26. In a machine for carding safety pins, pin feeding mechanism, a cooperating open pin carrier to support a spaced series of safety pins and to allow rectification of irregularities therein, a relatively movable card support to arch up a correspondingly slotted pin card in connection with said carrier and to force portions of said safety pins through the card slots, and feeding means for inserting a locking strip between the concave face of the pin card and the inserted portions of the pins.
27. In a machine for carding safety pins, a pin carrier to support a spaced series of safety pins, a relatively movable card support to support a correspondingly slotted pin card, and means to arch up said pin card and to force portions of said safety pins through the card slots.
28. In a machine for carding safety pins, a pin carrier to support a spaced series of safety pins, a relatively movable card support for a pin card formed with a correspondingly spaced series of transverse pin slots, means to insert portions of said safety pins through the card slots, and strip feeding and guiding means for longitudinally inserting a paper locking strip between the opposing face of the pin card and the inserted portions of the pins.
29. In a machine for carding safety pins, a pin carrier to support a spaced series of safety pins, a relatively movable support for a pin card, means to insert portions of said safety pins through the card slots, and means for longitudinally inserting a locking strip between the opposing face of the pin card and the inserted portions of the pins.
30. In a machine for carding safety pins, a pin carrier to support a series of safety pins, relatively movable means to support and transversely arch up a transversely slotted pin card and insert point portions of said safety pins through the card slots, and means to automatically insert a locking strip between the inserted portions of the pins and the opposing face of the pin card to detachably secure the pins thereto.
31. In a machine for carding safety pins, a pin carrier to support a series of safety pins, relatively movable means to transversely arch up a transversely slotted pin card and insert portions of said safety pins through the card slots, and means to automatically insert a locking strip between the inserted portions of the pins and the pin card.
32. In a machine for carding safety pins, a pin carrier to support a series of safety pins, means to support and arch up a pin card formed with slots of less size than said

safety pins, means to insert portions of said safety pins through the card slots, and feeding means for inserting a locking strip between the inserted portions of the pins and the opposing surface of the pin card to detachably secure the pins thereto.

33. In a machine for carding safety pins, a pin carrier to support a series of safety pins, means to support a pin card formed

with slots of less size than said safety pins, ¹⁰ means to insert portions of said safety pins through the card slots and means for inserting a pin-retainer strip between corresponding portions of the several pins and one face of the slotted card. ¹⁵

In testimony whereof, I have signed this specification.

HENRY M. GLEASON.
